ORNAMENT FOR CANDLELIGHTS

Myer Riesman, Chestnut Hill, Mass., assignor to
Royal Electric Company, Inc., Pawtucket, R. I.,
a corporation of Rhode Island

Application October 29, 1952, Serial No. 22,031

Term of patent 14 years

(Cl. D29—1)

To all whom it may concern:

Be it known that I, Myer Riesman, a citizen of the United States, residing at Newton, in the county of Middlesex and State of Massachusetts, have invented a new, original, and ornamental Design for an Ornament for Candlelights, of which the following is a specification, reference being had to the accompanying drawings, forming a part thereof.

Fig. 1 is a front elevational view of an ornament for candlelights showing my new design;

Fig. 2 is a side elevational view looking to the left of Fig. 1 with the side opposite Fig. 2 being substantially the same; and,

Fig. 3 is a sectional view taken on line 3—3 of Fig. 1.

I claim:

The ornamental design for an ornament for

candlelights, substantially as shown and described.

MYER RIESMAN.
